UNITED STATES PATENT OFFICE.

ALBERT L. CONNELLY, OF DETROIT, MICHIGAN, ASSIGNOR OF ONE-HALF TO JAMES J. CONNELLY, OF DETROIT, MICHIGAN.

METHOD OF EXCAVATING.

Application filed February 24, 1921. Serial No. 447,631.

To all whom it may concern:

Be it known that I, ALBERT L. CONNELLY, a citizen of the United States of America, residing at Detroit, in the county of Wayne 5 and State of Michigan, have invented certain new and useful Improvements in Methods of Excavating, of which the following is a specification, reference being had thereto to the accompanying drawings.

For digging tunnels, sewers and similar excavations large machines have been employed or hand spades or shovels employed, especially in a clay or loamy soil, devoid of large rocks. In the first instance considerable time and labor are required to place, 10 adjust and operate the large excavating machines, and in the latter instance the work is laborious and slow.

For digging ditches, drains and trenches, 20 various kinds of ditch and trench machines have been employed requiring careful operation and more or less mechanical skill or familiarity with the machines.

It is believed any tool that may be operated by power and controlled to a certain extent by unskilled labor will meet with approval as a substitute for the large excavating machines and the "back tiring" pick and shovel. Such a tool I have designed and it may be advantageously used 30 in excavating small tunnels and sewers in soft or clay earth.

The tool permits of a tunnel being dug or mining operations carried on by a new method, and the construction of the tool and the manner of using it will be herein-after described and then claimed, and reference will now be had to the drawing, where-in:

Figure 1 is a perspective view of the earth paring or scooping device;

Fig. 2 is a longitudinal sectional view of the same;

Fig. 3 is a cross sectional view of the device;

Fig. 4 is a perspective view of a modified form of the device;

Fig. 5 is a horizontal sectional view of the partially completed tunnel or sewer illustrating my method of excavating, and

Fig. 6 is a cross sectional view of the same.

The present method of digging a tunnel or sewer in soft earth is to provide the earth 55 with a vertical opening or shaft 1 of desired

depth and then start a lateral cylindrical bore 2 in the direction the tunnel is to take from the opening 1. The bore 2 may be excavated by hand tools or large machines and as the work progresses the bore is provided with a lining 3 to prevent cave-ins and afford a conduit. It is on the bottom of the tunnel that small gauge tracks 4 are laid for the movement of cars 6 employed for carrying the excavated earth from the diggings to the opening 1 where the cars are elevated and the earth removed therefrom.

To carry on operations in accordance with my method of excavating, I provide an earth paring or scooping device in the form of a ring like member 5 having an off-set or projected wall portion 7 provided with a sharp edge 8.

Suitably connected to the ring like member 5, opposite the off-set wall 7, is a drag bar 9 having its outer end provided with a clevis or coupling 10. Connected to the side walls of the ring like member 5 are braces 11 connected to the drag bar 9 adjacent its outer end, said braces and drag bar co-operating in providing a tripod bail for the member 5.

The device is adapted to be moved along the unfinished wall of the tunnel to pare or scoop strips of earth 12 therefrom and this is accomplished by placing the sharp edge 8 of the device in engagement with the earthen wall and pulling on the device so that a layer or strip of earth will be removed. As the strip is pared from the earthen wall it may be broken into lumps of desired size and cast into the car 6. For moving the paring or scooping device, I locate a windlass or pulley device 13 within the finished portion of the tunnel and this windlass or pulley device may be somewhat in the form of a hoisting engine or power winch electrically driven and suitably controlled by an operator at the winch. The

winch is suitably anchored and attached thereto is a cable 14 which extends to the unfinished end of the tunnel and is trained about a pulley block 15 attached to the clevis 10, said cable extending back to the winch where it is attached to and wound on the drum of the winch, so that when the winch is operated the paring device will be pulled towards the winch and may be guided by a laborer within the tunnel.

After each pulling operation the laborer retracts the paring device to obtain a fresh grip in the earth and these operations are carried on until the tunnel is of desired 5 diameter and length.

In starting the tunnel, I prefer to dig the opening 1 and then start a room or hall 16 in a lateral direction from the bottom of the opening 1. The paring device is then used 10 on both of the longitudinal walls of the hall 16 until a semi-cylindrical or arched opening 17 is produced, representing the upper half of the tunnel. Then, the bottom of the opening 17 may be scooped out to start the 15 cylindrical bore 2, and thereafter the paring or scooping device is used as shown in Fig. 5.

When a hard shale or indurate earth is encountered a paring or scooping device 20 may be used, as shown in Fig. 4, this device being similar to that shown in Fig. 1, with the exception that the wall 7 is provided with a plurality of tines 18 which will co-operate with the sharp edge 8 in removing quantities 25 of earth from the side walls of an incomplete tunnel.

While in the drawings there are illus-

trated the preferred embodiments of my invention, it is to be understood that the structural elements are susceptible to such 30 changes as fall within the scope of the appended claim.

What I claim is:—

A method of digging a cylindrical tunnel or similar subway, consisting of first 35 digging a vertical hole in the ground to a desired depth; second, digging a narrow lateral passage way in the direction in which the tunnel is to extend with the height of the passage corresponding to a radius of 40 the tunnel when complete; third, removing strips of earth from the side walls of the passage way to form an upper semi-cylindrical passage way, and fourth, removing 45 strips of earth from the floor of the semi-cylindrical passage way to convert said passage way into a cylindrical passageway.

In testimony whereof I affix my signature in presence of two witnesses.

ALBERT L. CONNELLY.
